XF 0 14,007

June 26, 1883.

Design No. 14,007,

DESIGN FOR A PLASTER CENTER-PIECE.

UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,007, dated June 26, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented and produced a new and original design for Plaster Center-Pieces for Rooms, of which the following is a true and correct specification, reference being had to the accompanying engraving forming a part 10 thereof.

My design is fully shown in the engraving annexed hereto; and it consists of a decorated ring, A, the groundwork of which is ornamented with Japanesque flowers B with dividing-blocks C at the circumference of the ring, and forming part of the base of the wings hereinafter described. To this decorated ring I add heart-shaped wings D of scallop-work, terminating in three rosettes, as shown in the 20 engraving accompanying this specification. I

vary this arrangement of my design by leaving off, when so desired, two of the wings, leaving it an elliptical shape; or the wings may be left off altogether whenever the room to be decorated may, from its size or from other circumstances, 25 require this modification to be made.

I claim—

1. A decorated ring with the groundwork of Japanesque flowers, dividing-blocks, and heart-shaped wings of scallop-work terminating in rosettes, substantially as shown and described. 30

2. A decorated ring, with groundwork of Japanesque flowers, with dividing-blocks at the circumference thereof, substantially as shown 35 and described.

WILLIAM F. KELLETT.
